UNITED STATES PATENT OFFICE.

GATES A. CLARK, OF ROCHESTER, NEW YORK, ASSIGNOR TO THE CLARK'S
COKING AND SMOKELESS FURNACE COMPANY, OF SAME PLACE.

COKING-FURNACE.

SPECIFICATION forming part of Letters Patent No. 415,022, dated November 12, 1889.

Application filed April 30, 1888. Serial No. 272,292. (No model.)

To all whom it may concern:

Be it known that I, GATES A. CLARK, of Rochester, in the county of Monroe and State of New York, have invented an Improvement 5 in Coking-Furnaces, of which the following description, in connection with the accompanying drawings, is a specification, like letters on the drawings representing like parts.

This invention relates to coking-furnaces 10 of that class in which soft or bituminous coal, wood, or other carbonaceous material is coked and the volatile products driven off by heat caused to pass up through the fire-bed to assist in combustion, and to obtain a 15 maximum amount of heat from the said coal or other material.

This invention is an improvement upon the coking-furnace shown and described in another application, Serial No. 260,976, filed by 20 me January 17, 1888, and has for one of its objects to provide the wall of the furnace exposed to the heat in the fire-box or combustion-chamber with a water-back divided into two chambers, and preferably connected to 25 the boiler, to establish and maintain a circulation of water or other fluid first through one chamber and then through the other chamber, whereby the water is maintained a substantially long time in contact with the metal 30 water-back, and the latter is most thoroughly protected and the life of the said wall is prolonged.

Another feature of my invention consists 35 in providing a damper or valve adapted to close the outlet or opening connecting the chute or chamber containing the coal with the fire-box, whereby the volatile products in the coal are prevented from being drawn through the said opening directly into the 40 fire-box, thereby causing all or substantially all the volatile products to pass up through the fire-bed, thus obtaining a greater heating effect than was hitherto possible.

The particular features in which my invention consists will be pointed out in the claims 45 at the end of this specification.

Figure 1 is a vertical transverse section of a sufficient portion of a furnace to enable my invention to be understood, the section being 50 taken on line x x , Fig. 2; and Fig. 2, a hori-

zontal section of the furnace shown in Fig. 1 on line x' x' .

The furnace A, of brick or other suitable material, and having the fire-box or combustion-chamber a, provided with the usual 55 grate-bars a', contains a boiler a², supported at one end by the rear wall a³ of the combustion-chamber, the said boiler being herein shown as a fire-tube boiler.

The furnace A is provided with a wall a⁴, 60 of fire-brick or other refractory material, extended the length of the combustion-chamber and supported, as shown, by the front casting or wall a⁵ of the furnace and the wall a³. The wall a⁴ rests upon a hollow metallic casting b, 65 preferably supported by the front wall a⁵ and the wall a³, and divided, as shown, by the wall b' into two chambers b² b³, communicating together preferably near the front end of the said casting. The wall a⁴ supports, as herein shown, 70 a T-rail b⁴, upon which rests an arch b⁵ of brick or other material, the said arch forming, with the wall a⁴ and side wall of the furnace, a chamber, which is divided longitudinally, as shown, by plates b⁵ b⁶, secured together by 75 bolts b⁷, into a chute or chamber b⁸, into which the coal or other material is supplied through a suitable door d^x (shown by dotted lines in Fig. 1) and a passage b⁹, the plate b⁵ being inclined toward the plate b⁶. 80

The coal or other material to be coked falls upon auxiliary grate-bars c, supported, as shown, on a box c', forming an auxiliary ash-pit, provided with a suitable door c², by opening which a draft may be furnished to the 85 chute.

The metallic casting b does not extend to the grate-bars a', but is supported above the said bars a sufficient distance to leave an outlet or discharge opening c³, through which 90 the coal or other material resting upon the auxiliary grate-bars, and which has been coked, may be fed or discharged into the fire-box by a plunger or feeder, shown as a box or frame c⁴, secured to a carriage c⁵, having, 95 as herein shown, at suitable distances apart, rack-bars c⁶, having in mesh with them gears c⁷ on a shaft c⁸, extended outside the furnace-wall and provided, as shown, with a suitable handle or crank c⁹, by which to rotate said 100

shaft, the said carriage being guided, as shown, by suitable rollers or wheels c^{10} .

The auxiliary grate, as shown, is provided with suitable openings or spaces d , (see Fig. 5 2,) for the passage of the rack-bars c^6 as the plunger or feeder is moved forward to discharge the coke into the fire-box.

The chambers $b^2 b^3$ in the metallic casting are connected at one end of the said casting 10 with the boiler by pipes $e e'$, respectively, the pipe e' , as shown, being connected to the bottom or lower part of the boiler and the pipe e to the upper part, so that the heavier or cold water or fluid at the bottom of the 15 boiler may flow through the pipe into the chamber b^3 and thence into the chamber b^2 , from whence it is forced through the pipe e into the boiler above the cold-water line. It will thus be seen that the metallic casting b 20 forms a water-back, through which a circulation of water is maintained, the said water reducing the temperature of the casting, preventing it from being burned out, and thereby prolonging the life of the furnace, at the 25 same time enabling steam to be generated in the boiler in a shorter time.

To prevent the volatile products from being drawn directly from the chute into the fire-box through the opening c^8 , which might 30 occur when the draft is substantially strong, I have provided a damper or valve f , of fire-brick or other refractory material, located, as shown, below and substantially in line with the water-back and movable in suitable 35 guides f' , secured to the walls of the furnace between the box c' and the grate-bars a' , the said valve or damper being movable, as shown, by gears f^2 on a shaft f^3 and in mesh with rack-bars f^4 , attached to the said damper or 40 valve, the said shaft being rotated from outside the furnace in any suitable manner.

When the damper or valve f is closed, the volatile products in the coal or other material to be coked, and which are driven off by heat, 45 are caused to pass up through the chute b^7 , through the passage b^7 , and up through the grate-bars a' and fire-bed thereon, as indicated by arrows in Fig. 1, thus obtaining a maximum yield of heat.

50 To expedite the coking process the door c^2 or a damper therein may be opened.

I prefer to connect the water-back with the boiler; but it is evident that the said water-back may be connected with a reservoir or 55 other source of supply located outside the furnace. By dividing the water-back into two chambers and causing the water to flow through one and then through the other of said chambers the said water is maintained 60 for a longer time in contact with the metal water-back, and the latter is thereby most effectually protected.

I claim—

1. In a coking-furnace, the combination, 65 with the wall between the main furnace and the coking-furnace exposed to the heat in the fire-box or combustion-chamber, of a water-

back supporting said wall and composed of a casting having the dividing-wall b' to form chambers $b^2 b^3$, communicating with each other 70 and connected to the boiler to establish and maintain a circulation of water or other fluid, substantially as described.

2. In a coking-furnace, the combination, 75 with a fire-box and a grate therein, of a wall a^4 , provided with a water-back, a chute or chamber to receive the material to be coked, a flue or passage connecting said chute with the fire-box below the grate, and a plunger or feeder to discharge the material into the fire- 80 box, substantially as described.

3. In a coking-furnace, the combination, 85 with a fire-box and grate therein, of a wall a^4 above the grate-bars to form a discharge outlet or opening c^3 , a chute or chamber to receive the material to be coked, a flue or passage connecting said chute with the fire-box below the grate, and a valve or damper to close the opening c^3 , substantially as described.

4. In a coking-furnace, the combination, 90 with a fire-box and grate therein, of a dividing-wall provided with a water-back located above the grate to form a discharge outlet or opening, a chute or chamber to receive the material to be coked, a flue or passage connecting said chute with the fire-box below the grate, a plunger or feeder to discharge the material into the fire-box; and a valve or damper to close the said discharge outlet or opening, 95 substantially as described.

5. In a coking-furnace, a fire-box, a grate therein, a boiler, a dividing-wall provided with a water-back connected to said boiler, a dividing-plate forming with said wall a chute or chamber to receive the material to be coked, 100 and a flue or passage for the volatile products contained in said material, combined with a plunger or feeder to discharge the coke into the fire-box, substantially as described.

6. In a coking-furnace, a fire-box, a grate 110 therein, a boiler, a dividing-wall provided with a water-back connected to said boiler, a dividing-plate forming with said wall a chute or chamber to receive the material to be coked, and a flue or passage for the volatile products 115 contained in said material, combined with a plunger or feeder to discharge the coke into the fire-box and with a valve or damper to close said discharge-outlet, substantially as described.

7. In a coking-furnace, the combination, 120 with a fire-box and a grate therein, of a wall a^4 , located in the fire-box and forming with the side wall of the furnace a chute or chamber to receive the material to be coked, a flue or 125 passage connecting said chute with the fire-box below the grate, and a water-back forming part of the wall a^4 and provided with a water inlet and outlet, by which circulation of water or other fluid may be maintained through the water-back, substantially as and for the purpose specified.

8. In a coking-furnace, the combination, 130 with a combustion-chamber and grate-bars

therein, of a coking-oven provided with a flue connecting said oven with the combustion-chamber below the grate-bars, a wall a^4 , separating said oven and chamber, and a water-back supporting said wall and connected to the boiler to establish and to maintain a circulation of water or other fluid through the water-back, substantially as described.

9. In a coking-furnace, the combination, 5
10 with a combustion-chamber and grate-bars therein, of a coking-oven provided with a flue connecting said oven with the combustion-chamber below the grate-bars, a wall a^4 , separating said oven and chamber, and a water-

back supporting said wall and composed of a 15 metal casting having a dividing-wall b' to form chambers b^2 b^3 , connected to the boiler to establish and to maintain a circulation of water or other fluid through the water-back, substantially as described. 20

In testimony whereof I have signed my name to this specification in the presence of two subscribing witnesses.
